TOOL FOR APPLYING AND REMOVING WHEEL BALANCING WEIGHTS

Ralph W. Mills, Kokomo, Ind., assignor to K-D Manufacturing Company, Lancaster, Pa., a corporation of Pennsylvania

Filed Feb. 6, 1961, Ser. No. 63,828

Term of patent 14 years

(Cl. D93—4)

FIG. 1.

FIG. 2.

FIG. 3.

FIG. 4.

FIG. 5.

FIG. 1 is a perspective view of a tool for applying and removing wheel balancing weights showing my new design.

FIG. 2 is a top plan view thereof.

FIG. 3 is a side elevational view thereof.

FIG. 4 is an end view thereof looking at the lefthand end of FIGURE 3.

FIG. 5 is an end view thereof looking at the righthand end of FIGURE 3.

I claim:

The ornamental design for a tool for applying and removing wheel balancing weights, substantially as shown.
